UNITED STATES PATENT OFFICE.

CHARLES DESHLER, OF NEW BRUNSWICK, AND EDWIN J. MCALLISTER,
OF NEWARK, NEW JERSEY.

PHOTOMETER.

SPECIFICATION forming part of Letters Patent No. 640,882, dated January 9, 1900.

Application filed June 16, 1898. Serial No. 683,632. (No model.)

To all whom it may concern:

Be it known that we, CHARLES DESHLER, of New Brunswick, in the county of Middlesex, and EDWIN J. MCALLISTER, of Newark, in the 5 county of Essex, State of New Jersey, citizens of the United States, have invented certain new and useful Improvements in Photometers, of which the following is a specification.

Our invention relates to various new and 10 useful improvements in photometers, which improvements are especially adapted for use with photometers for standardizing or determining the candle-power, voltage, or efficiency of incandescent electric lamps.

15 The principal object of our invention is to produce a portable photometer—that is to say, an instrument of this type which under operative conditions will have sufficient length to enable the proper accuracy of measurement 20 to be accomplished and at the same time will be capable of being so arranged as to occupy only a relatively small space in transportation. We prefer to so arrange the parts comprising the improved photometer that when they are 25 brought together for transportation they will constitute a compact and essentially rectangular package capable of being contained in a case of moderate size. A photometer which is sufficiently extended to possess the desired 30 accuracy and at the same time can be conveniently transported is a desired instrument in this art, since the only photometers now on the market are more or less cumbersome and generally require special tables or stands for 35 their reception.

A further object of our invention is to produce a new standard light which shall be capable of maintaining an absolutely-constant candle-power during extended periods of 40 time. We find that by employing a light-producing device, such as a kerosene-lamp having a normal candle-power, and by operating the same as a standard of very much reduced candle-power a practically uniform and un- 45 varying standard of light will be secured.

A further object of the invention is to provide means by which without unnecessary complication the light standard may be properly standardized and subsequently be used 50 in the standardization of electric lamps, either

in determining the candle-power of such lamps, their voltage, or their efficiency.

A further object of the invention is to provide minor improvements in the construction and arrangement of the elements as will con- 55 duce to the successful and convenient opera- tion thereof, all as will be more fully herein- after described and claimed.

In order that our invention may be better understood, we illustrate in the accompany- 60 ing drawings, which form a part of this speci- fication, the preferred form of photometer and the preferred arrangement of the individual elements thereof. The device thus illustrated we consider to be the preferable 65 embodiment of our invention; but it will be obvious from the following description that various modifications may be made therein as will be suggested to those skilled in the art to which our invention relates. 70

In the drawings, Figure 1 is a perspective 75 of the apparatus ready for operation and view- ing the same from the front; Fig. 2, a rear elevation thereof; Fig. 3, a plan view; Fig. 4, a sectional view on the line 44 of Fig. 3, illus- 80 trating the joint between the scale-carrying frame and the two standards therefor; Fig. 5, a detail view illustrating the preferred joint between the supplemental section carrying the rheostat and the electric connections and 85 the main frame or base, the view being taken above the line 55 of Fig. 3; Fig. 6, a section 90 on the line 66 of Fig. 3, illustrating the pre- ferred character of joint between the other supplemental section and the main frame; Fig. 7, a perspective view illustrating the parts 95 nested together for purposes of transpor- tation; Fig. 8, a cross-sectional view through the same, and Fig. 9 a diagram illustrating the preferred electrical connections. 100

In all of the above views corresponding parts are represented by the same numerals of ref- erence.

1 represents the main frame or base of the device, and 2 and 3 supplemental frames re- 95 movably or detachably carried at the ends of the main frame. Each of the sections 2 3 preferably comprises two essentially parallel strips 44; but for convenience in nesting the strips of the section 2 are arranged closer to- 100

gether than the strips of the section 3. The inner ends of the strips comprising the sections 2 and 3 are received in shallow recesses 5 in the main frame 1, and said sections are 5 removably secured to the main section by means of latches 6, which are of any desired type. Extending up from the base 1 are two tubular standards 7. Each of these standards is provided with a vertical slot 8, cut in 10 the upper end thereof, so as to receive a scale-carrying frame 9, said frame comprising a plug 10 at each end, fitting within the standards 7, and two parallel connecting-rods 11 11, which fit within the slots 8. Rods 11 carry 15 a scale 12, which has indicated thereon figures and cross-lines representing the candles of light. Movable longitudinally on the rods 11 11 is a light frame 13, having a handle 14, by which the frame may be shifted, and carrying a spot-box 15 of any desired type.

The spot-box shown consists of a generally open rectangular or cubical frame carrying a central vertical partition having an opening therein, in which opening is placed a sheet 25 of white paper having a central spot of paraffin or other greasy material and two mirrors arranged at an angle to the central partition and by which a reflection of the paper disk, with the spot, may be obtained by the 30 observer looking into the spot-box from the front of the apparatus. The spot-box carries a pointer 16, which co-operates with the scale 12.

The supplemental section 2 carries a rheostat or adjustable resistance 17, which preferably comprises a closely-wound coil of resistance material, such as German-silver wire, the coils being sufficiently separated for purposes of insulation, and over which a contact-ring 40 18 slides, so as to increase or decrease the number of turns in circuit and to thereby vary the electromotive force of current affecting the lamp which is being tested. Section 2 also carries, at a definite distance with respect 45 to the scale 12, a standard 19, on the upper end of which is mounted an incandescent-lamp socket 20 for receiving either the standard lamp, by which the light standard will be compared, or any lamp the candle-power, voltage, or efficiency of which is to be tested. The standard 19 comprises, preferably, a tubular support 21, in which is mounted a rod 22, the socket 20 being carried by said rod, and a set-screw 23 being employed to lock the rod 22 50 at any position in vertical movement. The said rod 22 may carry a collar 24, adjustable thereon and secured in place by a set-screw 25, and by means of which the proper position of the standard incandescent lamp having 55 been once determined it will be always maintained by the engagement between the collar 24 and the top of the tube 21.

The supplemental frame 3 carries a standard light-giving device, which is shown as 60 comprising an ordinary petroleum-oil lamp 26, the oil well or fount 27 of which is verti-

cally adjustable on two standards 28 by means of set-screws 29. The lamp 26 is preferably provided with two wicks, which are arranged at right angles to the direction of the scale 70 12, and the normal candle-power of said lamp is, preferably, much greater than the standard thereof which is to be utilized in the testing of incandescent lamps. In practice we find that by employing an ordinary petroleum-lamp having a normal candle-power of about 75 thirty-two candles and by operating the same at a candle-power of about eight candles it will constitute a practically constant and uniform standard light of the latter candle-power, which will not vary appreciably during 80 relatively long periods of time and by which a substantially exact standardization of incandescent lamps may be secured. By arranging the lamp 26 so as to be vertically adjustable on the standards 28 and by making the standard 19 so that one section thereof may telescope within the other the standard light and the lamp which is being tested may be always mounted in the desired plane with 85 the spot-box. For purposes of convenience we provide the section 3 with a number of dead or blind sockets 30, in which may be received a series of standard incandescent lamps 31 of varying candle-powers and voltages. These 90 lamps when thus placed will be below and to either side of the rays of the standard light, so that their presence will not affect in any way the operation of the device.

The supplemental section 2 is provided on 95 either side near the end thereof with an insulated strip 32 33, made, preferably, of hard rubber or vulcanized fiber. The strip 32 is provided with two binding-posts 34 and 35, to which the main-line wires are carried. The 100 binding-post 35 (see Fig. 9) is connected by a wire 36 to one end of the wire of the resistance 17. The other binding-post 34 is connected by a wire 37 to a binding-post 38.

39 is a binding-post on the strip 32, and 40 105 is a switch which may be employed when desired to connect the binding-posts 38 and 39.

The strip 33 is provided with three binding-posts 41, 42, and 43, a switch 44 being placed between the binding-posts 41 and 42 110 when it is desired to connect the same. The binding-post 43 is connected by a flexible wire 45 with the current-collecting ring 18, which works over the resistance 17. The socket 20 is connected by wires 46 between the binding-posts 39 and 41. With the switches 40 and 44 closed between the binding-posts 38 and 39 and 41 and 42, respectively, current to a lamp in the socket 20 will pass from the binding-post 35, wire 36, resistance 17, collecting-ring 18, wire 45 to binding-post 43, thence by a wire 47 to binding-post 42, switch 44, binding-post 41, socket, lamp, wire 46, binding-post 39, switch 40, binding-post 38, wire 37 to binding-post 34. The resistance will therefore be included in series with the lamp, and by shifting the collecting-ring 18 with respect 125 130 135

to the resistance-wire a greater or less number of turns may be included in this circuit, so as to vary the electromotive force at the lamp.

In order to measure the voltage of the current affecting the lamp, a voltmeter 48 is placed in circuit across the lamp-terminals and preferably between the binding-posts 38 and 42, as shown in Fig. 9. If it is desired to measure the current affecting the lamp, an ammeter 49 may be employed, connecting the binding-posts 41 and 42, and when this ammeter is used the switch 44 will, of course, be opened. By a comparative reading of the voltmeter 48 and ammeter 49 the efficiency of any lamp in the socket 20 will be secured in the usual way; but a direct reading of this efficiency may be secured by employing a wattmeter 50, the pressure-terminals of which are connected between the binding-posts 38 and 42 and the lamp-terminals of which are connected between the binding-posts 39 and 41. When this wattmeter is used, therefore, the switch 40 will be opened.

If desired, in the testing of incandescent electric lamps the socket 20 may be rotated in any suitable way as is now common in this art, whereby the entire light-giving capacity of the lamp may influence the spot-box, as will be understood.

In using the apparatus we first properly standardize the lamp 26. This is done in the following way: We first take a standard incandescent electric lamp of a known voltage and candle-power, which is placed in the socket 20. The lamp 26 is then lighted, and the spot-box is shifted on the guide-rods 11 until the pointer 16 indicates the candle-power of the standard electric lamp. Let us assume that the standard electric lamp employed is of sixteen-candle power at a voltage of 101.3 volts. Pointer 16 will therefore be moved to the figure "16" on the scale, and the collecting-ring 18 will be shifted on the resistance until the pressure between the binding-posts 38 and 42 exactly corresponds to 101.3 volts, the known standard of the lamp. The wicks of the lamp 26 are then adjusted until the reflections of the spots in the two mirrors of the spot-box read absolutely alike, when it will be known with entire certainty that the lamp 26 will be standardized to accord exactly with that of the standard lamp employed. Having thus standardized the lamp 26 and particularly when the standard used is materially below the light-giving power thereof, we have found from actual experience that this standard does not vary perceptibly during long periods of time. It is, however, desirable to check the lamp 26 whenever convenient in order that it may be determined with certainty that the standard is correct.

Having standardized the lamp 26, we proceed with the testing of incandescent lamps in the following manner: The lamp to be tested is placed in the socket 20 and connected into the circuit with the resistance 17 in se-

ries therewith, as explained. By maintaining the pressure on the lamp at the required voltage at which it is intended to operate, which is done by shifting the collecting-ring 18 of the resistance 17 and by shifting the spot-box laterally on the guide-rods 11 until the two spots read exactly alike, the pointer 16 will indicate on the scale the exact candle-power of the lamp being tested. If, however, the lamp is of a known or represented candle-power and it is desired to ascertain if the voltage indicated is sufficient to produce the desired candle-power, the spot-box will be moved until the pointer 16 indicates the represented or known candle-power of the lamp, and the collecting-ring 18 will be shifted relatively to the resistance, so as to vary the brilliancy of the light until the two spots read alike. The voltmeter will then indicate the pressure of the current affecting the lamp to produce the desired candle-power. By taking comparative readings of both the voltmeter and the ammeter to obtain the pressure on the lamp and the current affecting it a determination of the lamp's efficiency will be secured, or if a wattmeter is employed, as described, these two factors will be indicated on the scale thereof and for the same purpose.

When it is desired to nest the parts of the photometer together for purposes of shipment, the sections 2 and 3 are disengaged from the main portion by operating the latches 6. The plugs 10, carrying the guide-rods 11 and spot-box and scale, are then removed from the standards 7. The section 2 is then placed upon the frame 1, with the two strips 44 thereof on either side of the standards 7 and with the standard 19 immediately behind and extending parallel with one of said standards 7, the end of the resistance 17 being in contact with the other of said standards. The section 3 is then placed upon the base 1, with the strips 44 thereof extending parallel and practically in contact with the strips of the section 2, 110 with the test-lamps 31 on either side of the resistance 17, and with the lamp 26 immediately behind the standard 7 at that side. The plugs 10 are then inverted and again introduced into the upper ends of the standards 7, 115 with the spot-box hanging downward immediately in front of the resistance 17 and about the sections 2 and 3, which are in contact with the main frame 1. This produces a very compact and portable package, which may be contained in a relatively small case and capable of being quickly reassembled for use. The chimney of the lamp 26 may be now placed adjacent to the package in any suitable way.

If desired, for the purpose of excluding outside light from the vicinity of the spot-box two opaque screens 51 may be employed, which are carried on light wire standards 52, carried by clamping-collars 53 on the standards 7. These screens will be sufficiently flexible to be rolled up out of the way when the apparatus is packed for shipment.

Having now described our invention, what we claim as new, and desire to secure by Letters Patent, is as follows:

1. As a new article of manufacture, a photometer for testing incandescent electric lamps and comprising a main section carrying a spot-box and scale, and two supplemental sections movable with respect to the main section, one of said supplemental sections carrying a standard light and the other carrying the electric light to be tested, a rheostat, and connections for a voltmeter and ammeter, substantially as set forth.
2. As a new article of manufacture, a photometer for testing incandescent electric lamps and comprising a main section carrying a spot-box and scale, and two supplemental sections movable with respect to the main section, one of said supplemental sections carrying a standard light and the other carrying the electric light to be tested, a rheostat, and connections for a voltmeter, an ammeter and a wattmeter, substantially as set forth.
3. As a new article of manufacture, a photometer for testing incandescent electric lamps and comprising a main section carrying a spot-box and scale, and two supplemental sections movable with respect to the main section, one of said supplemental sections carrying a standard light and the other carrying the electric light to be tested, a rheostat, connections for an ammeter, and a switch for short-circuiting said ammeter, substantially as set forth.
4. As a new article of manufacture, a photometer for testing incandescent electric lamps and comprising a main section, two

vertical standards carried by said main section, a spot-box and scale carried by said standards, two supplemental sections each comprising two parallel strips, one of said sections carrying a standard light and the other carrying the light to be tested, and means for removably securing said supplemental sections to the main section, whereby the supplemental sections may be removed and nested upon the main section with the parallel strips thereof extending on either side of the scale-supporting standards, substantially as set forth.

5. As a new article of manufacture, a photometer for testing incandescent electric lamps and comprising a main section, two vertical standards carried by said main section, a spot-box and scale carried by said standards and capable of being inverted with respect to the same, two supplemental sections each comprising two parallel strips, one of said sections carrying a standard light and the other carrying the light to be tested, and means for removably securing said supplemental sections to the main section, whereby the supplemental sections may be removed and nested upon the main section with the parallel strips thereof extending on either side of the scale-supporting standards, substantially as set forth.

This specification signed and witnessed this 19th day of May, 1898.
